DESIGN FOR A CONSOLE BAR CELLARETTE

David Dillon, New York, N. Y.

Application October 19, 1937, Serial No. 72,308

Term of patent 3½ years

To all whom it may concern:

Be it known that I, David Dillon, a citizen of the United States and residing at New York city, in the county of New York and State of New York, have invented a new, original, and ornamental Design for a Console Bar Cellarette, of which the following is a specification, reference being had to the accompanying drawing, forming part thereof, and in which

Fig. 1 is a top perspective view of the console bar cellarette, showing my design in closed position.

Fig. 2 is a similar top perspective view showing the cellarette opened.

The distinctive features of the design consist in the two transverse floor support members extending forwardly of the front of the cellarette, and the top member which terminates short of the outside faces of the side portions of the cellarette, as shown.

I claim:

The ornamental design for a console bar cellarette, substantially as shown and described.

DAVID DILLON.
